ROSE PLATE FOR KNOBS OR THE LIKE

Morris Loeb, New York, N.Y., assignor to Liberty Hardware Mfg. Corp., Long Island City, N.Y., a corporation of New York

Filed Jan. 30, 1967, Ser. No. 5,609

Term of patent 14 years

(Cl. D50—6)

FIG. 1

FIG. 2

FIG. 3

FIG. 1 is a top plan view of the rose plate for knobs or the like according to my invention;

FIG. 2 is a front elevation of the rose plate according to my invention; and

FIG. 3 is an enlarged transverse sectional view taken in the direction of arrows 3—3 of FIG. 1.

The dominant features of the design reside in the portions shown in full lines.

I claim:

The ornamental design for a rose plate for knobs or the like, substantially as shown and described.
